UNITED STATES PATENT OFFICE.

CARSON J. SHELDON, OF YOUNGSTOWN, OHIO.

SASH.

1,319,121.

Specification of Letters Patent.

Patented Oct. 21, 1919.

Application filed April 29, 1918. Serial No. 231,509.

To all whom it may concern:

Be it known that I, CARSON J. SHELDON, a citizen of the United States, residing at Youngstown, in the county of Mahoning 5 and State of Ohio, have invented certain new and useful Improvements in Sashes, of which the following is a specification.

This invention relates to metallic building structures, and more especially to window sashes; and the object of the same is broadly to produce a pivoted sash which may be swung within its frame to produce 10 ventilation.

Another object is to improve the construction of the mullion bars, their point of crossing with each other, and their points of juncture with the sash frame.

Another object is to improve the form of pivot employed.

20 Yet other objects will appear in the following specification and claims, and reference is made to the drawings, wherein:—

Figure 1 is an elevation of this improved window, taken from the outside,

25 Figs. 2 and 3 are vertical and horizontal sections respectively on the lines 2—2 and 3—3 of Fig. 1.

Fig. 4 is an enlarged cross section of the two-part mullion bar, before the members 30 or parts thereof are assembled,

Fig. 5 is an enlarged sectional detail through the pivot, and

Fig. 6 a side elevation thereof,

Fig. 7 is a perspective detail of a portion 35 of the horizontal mullion bar at its point of crossing with the vertical mullion bar, and

Figs. 8 and 9 are perspective details of the two members of the vertical mullion bar at said point of crossing,

40 Fig. 10 is a perspective detail showing the two bars where they cross,

Fig. 11 is an enlarged sectional detail on the line 11—11 of Fig. 1.

The window frame illustrated in the present case is made up of a top bar 1, side bars 2 connected about two thirds the way down by a cross stile 3, and a bottom bar 4 whose inner web 5 constitutes a glass ledge. The lower portions of the side bars will have 45

50 similar inner webs 6, the lower face of the stile will have a web 7, and if there is a central upright stile as shown at 8 it will have webs on both sides so that the lower fixed portion of the window yet to be described will be divided into two panels as 55 best seen in Fig. 1. The upper portion of

the window as here shown includes a swinging sash mounted on peculiar pivots yet to be described. All parts of this structure are of metal to receive the glass (if glass 60 panes are used instead of wooden panels) and it is one important feature of the present invention to so construct the various elements that they can be made from rolled steel bars, stamped with appropriate notches 65 and scoring, bent later where necessary, and assembled in a manner yet to be set forth. While I have shown the swinging sash as having one upright central mullion crossing 70 one horizontal mullion, it should be understood that this is only for the purpose of bringing out the construction at the point of crossing and there could of course be a greater number of mullions and smaller panes of glass if the structure be a window, 75 or panels of other materials if the structure be a door or shutter. Furthermore, where I have shown in Fig. 1 a complete window which would have to be hinged in the window casing if it were not removable, it 80 will be understood that the parts thereof above the cross stile 3 may constitute an upper sash and be duplicated below the stile in a lower sash, instead of having the lower portion of the structure fixed as described 85 above.

I have shown and will describe the horizontal mullion or bar as made in one piece and the upright mullion or bar as in two pieces, but these might be reversely disposed 90 without departing from the invention. The horizontal bar best seen in Fig. 7 comprises an inner web 10, an outer and somewhat narrower web 11 alined with the inner web, and two lateral flanges 12 at their point of juncture, each having a glass ledge 13. The whole is formed in one integral piece by rolling, stamping, or other appropriate process, and at the point where the vertical bar is to cross the horizontal bar the latter 100 is notched in its inner web as shown at 14, in its outer web as shown at 15, and completely through both the flanges as shown at 16.

The vertical bar is in two members as 105 best seen in Figs. 4, 8 and 9. One of these members has an inner web 20, two integral lateral flanges 22 with glass ledges 23, and two outstanding lips 24 which are thin enough to be pliable and which are spaced 110 from each other on the outer sides of the flanges so as to produce an interposed chan-

nel 25. The other member is of inverted T-shaped section, its shank 21 corresponding with the web 11 of Fig. 7 and its head 26 being of a size to enter said channel 5 25, after which the lips 24 are bent down over the edges of the head as indicated in dotted lines in Fig. 4; and, as indicated by the numeral 21 in Figs. 1 and 10, the outer web of this member is continuous and un- 10 broken from top to bottom of the sash frame. The inner member is notched through its lips, flanges, and into its web 20 as shown at 27 in Fig. 9, and the outer member is notched through its head and 15 into its shank as shown at 28 in Fig. 8. These notches occur in the two members at points to come opposite each other and to co-act respectively with the notches 14 and 15 in the horizontal bar shown in Fig. 7. 20 The result is that, when this horizontal bar is put in place within the sash frame and then the two parts of the vertical bar are applied and notched into it, the final turning down of the lips 24 over the head 25 26 as seen in Fig. 4 will produce a structure well illustrated in Fig. 10. To make a close fit of parts, the corners of the flanges are beveled off as shown at 30 in Fig. 7 and 31 in Fig. 9, and these bevels meet each 30 other as shown at 32 in Fig. 10.

The swinging sash frame is made up of a top bar 41 underlying the top bar 1 of the windowframe, two side bars 42, and a bottom bar 43 overlying the stile 3; and the 35 upper portion of the frame is flanged on the inner side as at 44 while the lower portion is flanged as at 45 on the outer side. Each flange extends around three sides of the frame and is carried thereby, so that when 40 the sash swings as shown in dotted lines in Fig. 2, the flanges move with it. Meanwhile, the window frame carries on its respectively opposite faces and at the upper and lower portions respectively, fixed fac- 45 ings 46 and 47. The lower ends of the outside facing strips 46 are cut off at 48, and the upper ends of the outer flanges 45 are cut off at 49 to produce a space on each side rail of the window for the reception of the 50 knuckles of the pivot to be described below.

In Figs. 5 and 6 are shown details of the preferred form of pivot which I employ. One member 52 may be called the fixed member, secured by bolts or screws to the 55 window frame, and the other member 50 may be called the movable member. It is in two parts connected by appropriate means such as the screws 51 and it is mounted on the swinging sash. The member 52 has a 60 pin 53 projecting loosely into a rather large socket 54 within the member 50, and filling the space between the outer wall of the pin and the inner wall of the socket is a ring or bushing 55. The member 52 is by pref- 65 erence channeled as at 56 around the base

of the pin 53 as seen in Fig. 5, and the bushing is of such length that it projects into this channel and assists greatly in centering the members one on the other and in taking up the wear occasioned by the respective movements. When the parts are properly assembled, it will be seen that the sash as a whole may swing within the upper portion of the window frame, turning on the alined pivots with ease, and the inner 75 flange 44 at the upper portion of the sash and outer flange 45 at the lower portion thereof will move respectively away from the top bar 1 and the stile 3 of the window frame and carry with them the mullions 80 and panels whether the latter be of glass or otherwise; and thereby ventilation is produced to the extent that the swinging sash is opened. I have omitted the illustration and description of any sash fastener 85 or window fastener, as these details form no part of the present invention.

The foregoing description and the drawings have reference to what may be considered the preferred, or approved form of my 90 invention. It is to be understood that I may make such changes in construction and arrangement and combination of parts, materials, dimensions, et cetera, as may prove expedient and fall within the scope of the 95 appended claims.

Having thus fully described my invention, what I claim as new and desire to secure by Letters Patent, is:—

1. In a window sash, the combination 100 with a mullion comprising inner and outer webs and lateral glass ledges integral with the webs, certain of said parts being notched; of a second mullion at right angles to the first and made up of two members notched 105 to complement the notches in the first mullion, and means for clamping said members to each other.

2. In a window sash, the combination with a mullion comprising inner and outer webs and lateral glass ledges integral with the webs, certain of said parts being notched; of a second mullion at right angles to the first and made up of two members notched to complement the notches in the first mul- 115 lion, one member comprising an inner web, lateral flanges, and a pair of pliable lips, and the other member comprising an outer web and a T-shaped head adapted for reception between said lips.

3. In a window sash, the combination with a mullion comprising inner and outer webs and lateral glass ledges integral with the webs, certain of said parts being notched; of a second mullion at right angles to the first and made up of two members notched 125 to complement the notches in the first mullion, one member comprising an inner web and integral lateral glass ledges and the other member being of T-shaped cross sec- 130

tion, and means for connecting said members after the parts have been assembled.

4. In a window sash, the combination with a mullion comprising inner and outer webs and lateral glass ledges integral with the webs, the inner and outer webs and the ledges being notched; of a second mullion in two members whereof the innermost comprises a web and a head constituting glass flanges and the outermost is of T-shaped section including a shank and a head, the former being notched through its head into its web and the latter in the opposite direction through its head into its web to complement the notches in the first-named mullion, and means for securing the members of the second-named mullion to each other.

5. A mullion crossing structure for windows and the like comprising a horizontal bar including an inner web, lateral glass ledges, and an outer web, the webs being notched on their outer edges and the ledges being notched completely through and in line with the other notches; and an upright bar made in two members, one including an inner web, lateral glass ledges, and parallel pliable lips on the ledges and this member being notched through its lips and ledges into its web, and the other member being of T-shaped section and notched through its head and into its shank, all ledges being beveled away on opposite sides of the notches therein, the whole for use substantially as described.

35 6. In a window sash, the combination with a mullion comprising inner and outer webs and lateral glass ledges integral with the webs, all of said parts being notched; of a second mullion at right angles to the first and made up of two members notched to complement the notches in the first mullion, one member having an inner web and a pair of pliable lips, and the other member comprising an outer web and a T-shaped head adapted for reception between said lips.

7. In a metallic sash structure, a mullion composed of two members each of approximately T-shaped cross-section and one of larger size than the other, said members being disposed with their cross-heads in back-to-back relation and their stems in alinement, the cross-head of the larger of said members having integral lips near its lateral edges turned into clamping relation 50 to the cross-head of the smaller member whereby said members are permanently interlocked.

8. In a metallic sash structure, a mullion comprising two members, each of approximately T-shaped cross section disposed with their cross-heads in back-to-back relation,

the cross-head of one member being of greater width than that of the other, and outstanding lips carried by the larger cross-head and turned over the edges of the 65 smaller cross-head and inward against its stem, for permanently interlocking said members.

9. In a metallic sash structure, a mullion comprising two members, each of approximately T-shaped cross-section disposed with their cross-heads in back-to-back relation, the cross-head of one member being of greater width than that of the other, and opposite flanges carried by the larger cross-head at a spaced distance from the lateral edges of the latter, said flanges being turned into confining relation to the lateral edges of the smaller cross-head for permanently interlocking said members.

10. In a metallic sash structure, a mullion composed of two members, each of approximately T-shaped cross-section and one of larger size than the other, said members being disposed throughout their lengths with their cross-heads in back-to-back relation and their stems in alinement, the cross-head of the larger of said members having integral flanges located intermediate its lateral edges and the corresponding edges of the 90 smaller member, said flanges being turned into clamping relation to the cross-head of the smaller member whereby said members are permanently interlocked.

11. A mullion crossing for metallic window sashes and the like, comprising a one-piece mullion bar of Latin cross form in cross section, the opposite webs constituting the vertical crossing member of said bar being of stepped formation at one side; said 95 bar having notches formed in the opposite lateral edges of the webs which constitute the stem member and having notches extending through the webs of said crossing member, said notches being in alined relation at 100 a medial point with respect to the ends of said bar; and a two-piece mullion bar crossing said one-piece bar and notched to complement with the notches in the latter, said 105 two-piece bar comprising two complementary members, each of T-shaped cross section, one of which is of larger size than the other, said members having their cross-heads permanently clamped together in back-to-back relation to form a bar of identical shape and 110 size with said one-piece bar.

In testimony whereof I affix my signature in presence of two witnesses.

CARSON J. SHELDON.
